Application January 13, 1942, Serial No. 426,600

5 Claims. (Cl. 234—36)

This invention relates to a time recording mechanism, more particularly for recording the time of arrival of carrier pigeons at their home station when freed from a distant point; accordingly, the mechanism adapts itself for use in pigeon racing contests. The mechanism is contained in a box into which the indicating bands on the legs of the pigeons are deposited in the order of the arrival of the pigeons at their home station, the mechanism being operated upon the deposit of each band, so that by means of a time stamp (which is incorporated in the mechanism) operating on a movable paper web, the pigeon arrivals are successively recorded. In such contests, each pigeon owner is provided with a box containing the timing mechanism and a committee or other designated authority inspects the mechanisms to see that they are in suitable condition and ready for operation, sets the clocks and closes the boxes, each having provisions to prevent or detect its re-opening until the box is returned to the committee. The pigeon owners then return to their home stations, following which his pigeons are released or freed by the committee. As each pigeon arrives at its home station, the indicating band on its leg is removed and placed in a cavity provided in the mechanism and the latter operated by the owner, to record the arrival. At a predetermined time, each box is opened by the committee and the bands in the respective cavities noted with respect to the successive time stamp impressions on the paper web, and comparisons made with similar impressions in the other boxes to determine the winning pigeons.

One object of the invention is to provide an improved mechanism of this character having signal means, operable automatically, to indicate to the operator or pigeon owner predetermined positions of the mechanism to prevent inaccurate or confused recordings on the paper web.

Another object of the invention is to provide an improved mechanism of this character wherein provision is made for supporting and feeding the paper web a predetermined distance during each operation of the mechanism and for automatically holding the paper support stationary while the time stamp is operating.

Another object of the invention is to provide an improved mechanism of this character wherein the driving connections between related parts are materially simplified to insure accurate operation and ready assembly.

Another object of the invention is to provide an improved mechanism of this character where-

in the operating parts are co-operatively related to prevent fraudulent recordings.

A further object of the invention is to provide an improved mechanism of this character wherein provision is made to suspend a section of inking material for the time stamp.

Other objects of the invention will be apparent to those skilled in the art to which my invention relates from the following description taken in connection with the accompanying drawings, wherein

Fig. 1 is a perspective view of a box or container enclosing a mechanism embodying my invention.

Fig. 2 is a top plan view, the cover of the box being broken away to show the mechanism.

Fig. 3 is a side elevation on the line 3—3 of Fig. 2.

Fig. 4 is a section on the line 4—4 of Fig. 2.

Fig. 5 is a section on the line 5—5 of Fig. 3.

Fig. 6 is a fragmentary section on the line 6—6 of Fig. 3.

Fig. 7 is a section on the line 7—7 of Fig. 3.

Fig. 8 is a section on the line 8—8 of Fig. 3.

Fig. 9 is a section on the line 9—9 of Fig. 4.

Fig. 10 is a section on the line 10—10 of Fig. 3.

In the drawings, 1 indicates a suitable casing enclosing the mechanism hereinafter set forth. The casing consists of a main section 1a and a hinged section 1b to permit access to the mechanism. These parts may be locked closed in any desired manner. The main and hinged sections of the casing are preferably of equal size in height, which facilitates access to parts of the mechanism and removal and replacement of windows 2, 2a, each of which fits recesses 3 formed in the adjacent side walls of the sections 1a, 1b (see Fig. 3). The window 2 is arranged in front of the dial or face of a clock, indicated as an entirety at 4 and suitably secured within the casing 1, being preferably secured to a base 1x removably mounted on the bottom wall of the casing section 1a. The base 1x is supported in spaced relation to the bottom wall to accommodate certain parts which are later referred to. The clock is provided with suitable stamping elements (see Fig. 7) operated by the clock and arranged to record the hour, minute and second each time the mechanism is operated (as later set forth), on a paper web 5. The paper web 5 is mounted on supports 6, 6', and fed from one to the other to receive successive time stamped records or impressions. The clock and stamping elements and the operating connections therebetween may be

55 of any desired construction for which reason they

are not illustrated and described in detail. The supports 6, 6', for the paper web 5 may be of any desired construction and both automatically actuated by operating parts of the mechanism, but in the preferred arrangement, as herein disclosed, only one support for the paper web is driven in the manner later set forth. The support 6 for the paper web 5 consists of an upright spindle 6a having a lower collar 6b and an upper collar 6c. The spindle 6a is suitably mounted on the base 1x. The collar 6c is removably secured to the upper end of the spindle 6a, whereby a roll of paper web 5 may be readily mounted on the spindle as shown in Fig. 5. As shown in Fig. 4, the collar 6c is formed with an internally screw threaded opening which threads on the upper, reduced end of the spindle against the resulting shoulder. 7 indicates as an entirety a frame comprising spaced uprights 7a, 7b, suitably secured to the base 1x and a plate 7c suitably secured to flanges provided on the upper ends of the uprights 7a, 7b. 6x indicates a leaf spring anchored at one end on the upright 7a and normally biased against the roll of paper web 5 to frictionally retard it from unwinding. The paper web 5 is guided around a pair of spaced posts 8, 8a, from the support 6 to the support 6', the latter being driven a predetermined distance during each operation of the mechanism. The posts 8, 8a, are suitably mounted at their lower ends in the base 1x and are spaced at opposite sides of and forward of a movable platen 9, when the latter is in normal position, so as to guide the web between the platen 9 and the stamping elements. 10 indicates a section or sheet of transfer material disposed between the stamping elements and that portion of the paper web 5 guided by the posts 8, 8a, in front of the platen 9. The transfer material may consist of carbon paper or woven material inked similar to typewriter ribbons. The end portions of the transfer section 10 are removably secured between clamping elements 11 which are spacedly mounted at or adjacent the opposite sides of the clock 4 and support the transfer section 10 in a transverse plane between the time stamp elements and the paper web 5. To provide the clamping elements 11, I provide rearwardly of the clock a thin sheet of metal 11a, which is secured to the base 1x and formed with an opening to expose the stamp elements. Along the opposite ends of the sheet 11a I provide angles 11a'. One side portion of each angle is suitably secured to the sheet 11a; whereas its other side portion forms a clamping wall 11b between which and a strip 11c the transfer section is removably clamped. Each strip 11c extends beyond the upper and lower edges of the transfer section 10 and is provided with pins 12 which slidably extend through openings formed in the adjacent wall 11b. The outer end of each pin 12 is provided with a head and between the head and the wall 11b, surrounding the pin, I provide a coiled expansion spring 13, which normally tends to move the pin endwise away from the wall 11b, and hence yieldingly presses the strip 11c toward the wall 11b to detachably secure the transfer section thereto. As shown, the walls 11b are disposed at right angles to the plane in which the transfer section is supported, so that relatively little spring tension on the strips 11c is required to support the transfer section 10; and this light spring tension permits each strip to be readily deflected either to insert a section of transfer material or take up on slack therein.

The platen 9 is provided on its face or front side with a pad or layer of relatively soft material 9'. On its rear side, the platen 9 is provided with a hollow boss 9" threaded internally to provide a screw thread connection with the outer end of a hollow reciprocatable member 14. The outer end portion of the member 14 extends through and slidably fits an opening 7', in the upright 7a whereas its inner end portion telescopes over and is slidably supported by a guide member 15, which is mounted on the upright 7b and extends inwardly therefrom. Within the reciprocatable member 15 and between the platen 9 and inner end of the guide member 15 I provide a relatively strong coiled expansion spring 16 arranged to be put under tension when the platen 9 is retracted (toward the right as viewed in Figs. 4 and 5) so that when the platen 9 is released, the spring 16 will impel the platen toward the stamp elements and effect an impression therefrom onto the paper web 5. At its inner end, the reciprocatable member 14 is provided with a collar 17 with which a cam 18 engages to retract the member 14 and then disengages it to release the member 14 for operation by the spring 16. 14a is a relatively light coiled spring surrounding the member 14 and interposed between the wall 7a and collar 17 for moving the member rearwardly following each operation of the platen. As will be observed, in the movement of the platen 9 under the influence of the spring 16, the spring 14a is compressed between the collar 17, and wall 7a, the tension thus stored up in the spring 14a being utilized to move the platen rearwardly out of engagement with the paper web 5, so that the latter is free to be moved or fed forwardly by the operation of the support 6', as later set forth. At one side the collar 17 is formed with a through opening 17a, in parallel relation to the axis of the member 14. A rod 19, which is supported on and extends inwardly from the upright 7b, extends through the opening 17a and through its engagement with the walls thereof it prevents rotative movement of the member 14 and maintains the collar 17 in a predetermined relation to the cam 18. The collar 17 may be secured to the member 14 in any desired manner, but preferably it is split, as shown in Fig. 9, and the split portions clamped to the walls of the member 14 by a screw 17b. The cam 18 is suitably fixed to a shaft 20 (which is later referred to) rotatably mounted in and extending through the base 1x and top wall 7c, its upper end being shaped for engagement by a crank (not shown) and related to an opening 20a formed in the top wall of the casing section 1b, whereby the shank of the crank may be applied to the shaft 20 to rotate it. 21 indicates a stud shaft extending upwardly from the top wall 7c. The shaft 21 has fixed to it a collar 21a, having a reduced lower end fitting an opening in the wall 7c, the shaft extending through the opening and an opening in the flange on the upper end of the upright 7a, so that by means of a nut 21b threaded on the lower end of the shaft, the walls 7a and 7c are secured together and the shaft 21 rigidly secured in position. The shaft 21 serves to removably and rotatably support the hub 22 of a disk 23, which is adapted to be rotated step-by-step in each operation of the mechanism by the shaft 20. The disk 23 is provided with holders into which the bands or indicating devices attached to and removed from the pigeons, are deposited. The holders preferably consist of cups 24 depending

from the disk 23, their open ends being flush with the top surface of the disk. The circumference of the disk 23 is divided into twelve equal imaginary sections, corresponding to the step-by-step operation of the disk in one revolution thereof. Ten of these sections are provided with cups 24 numbered 1 to 10, consecutively, one section is blank and designated S (to indicate the starting or setting position of the mechanism) and the remaining section is blank and designated F (to indicate the end of the recordings). As shown, the section marked S is in advance of the cup numbered 1 and the section marked F is rearward of the cup numbered 10 and adjacent to and in advance of the section marked S. Cups 24 are disposed below the blanks S and F for a purpose later apparent. Also, as shown, the cups and blanks are equal distances from the axis of the disk, so that each moves into registry with an opening 25 formed in the top wall of the casing section 1b, which opening permits the indicating devices removed from the pigeons, upon arrival thereof at their home station, to be deposited in the cups 24. In this arrangement, provision is made to record the successive arrival of one to ten pigeons.

The driving connections between the shaft 20 and disk 23 are constructed to (a) operate the latter one step (counter-clockwise as viewed in Fig. 2) each time the cam 18 retracts the platen 9 and releases it to make a time record or impression, which operation takes place in one complete rotation of the shaft 20, and (b) prevent reverse rotation of the disk (clockwise) or disconnection of the disk from the driving elements carried by the shaft 20 and rotated in either direction, so that fraudulent operations and time records cannot be effected.

The driving connections comprise the following: 26 indicates a plurality of slots formed in the marginal portion of the disk 23 and extending inwardly from its periphery. Due to the fact that in the starting position of the disk the blank S is in registry with the opening 25, a slot 26 is provided adjacent to and in advance of the cups 24 numbered 3 to 10, respectively, blanks F and S and cup numbered 1, but omitted from the margin adjacent to the cup numbered 2, whereby the disk periphery forms a stop, as later set forth, to prevent continued operations of the mechanism.

Each of the slots 26 is adapted to receive a pin 27 extending upwardly from a collar 28 disposed in a plane below the disk 23 and having a depending hub 28a suitably fixed to the shaft 20, so as to be rotated thereby, the engagement of the pin 27 with the end and front walls of the slot, during one rotation of the collar, serving to move the disk 23 one step to bring the adjacent rearward cup or blank (as the case may be) into registry with the opening 25 and the adjacent rearward slot 26 into position to receive the pin 27 for the succeeding rotative movement of the collar 28. As shown, the marginal portion of the collar 28 extends beyond the marginal portion of the disk 23 in the path of movement of the cups 24 and hence prevents rotative movement of the disk independently of the shaft 20 or during the movement of collar when the pin 27 is disengaged from the walls of each slot; but to permit rotation of the disk 23 by the engagement of the pin 27 with the walls of each slot 28, the marginal portion of the collar 28 is formed with a recess 28b, which accommodates the cup 24 adjacent that slot 26 into and out of which the pin 27 moves

in each operation. The pin 27 preferably extends upwardly to a point close to the inner surface of the top wall of the casing section 1b, so as to prevent lifting of the disk 23 (while the casing 1 is closed) far enough to disengage the pin and permit fraudulent operation of the disk.

29 indicates a separate shaft mounted in the wall 1c and base 1x and extending through the latter to provide a driving connection with the shaft 20, as later set forth. The shaft 29 extends through and slidably fits the hubs on the upper and lower ends of the support 6', to support the latter thereon and permit movement of the support endwise of the shaft. The upper end portion of the shaft 29, below the wall 1c, is provided with a laterally extending lug or pin 30 adapted to removably seat in a recess 31 formed in the hub on the upper end of the support 6'. The lower end of the support or spool 6' rests on a lever 32 which is suitably pivoted at its inner end on a standard 33 and normally biased upwardly by a spring 34 coiled around the shaft 29. As shown in Fig. 10 the hub 35 at the lower end of the support or spool 6' is provided at its lower end with a flange and the lever 32, which is formed with an opening through which the hub extends, is arranged between the lower end wall of the support 6' and the flange provided on the lower end of the hub 35. In this arrangement the spring is interposed between a collar 36, which is fixed to the shaft 29 and rests on the base 1x, and the hub 35 and normally acts through the latter to maintain the lever 32 and support 6' elevated, with the pin 30 seated in the recess 31, whereby rotation of the shaft 29 drives the support 6'. The lever 32, through its engagement with the flange on the hub 35, when pushed downwardly (see dotted lines in Fig. 10), serves to move or slide the support 6' downwardly endwise of the shaft 29, such movement effecting a disengagement of the recess 31 from the pin 30, whereby the support 6' is free to rotate in either direction, so that the paper web 5 wound thereon may be readily removed. The side wall of the support or spool 6', intermediate its ends, is provided with a resilient clip 37, under which the outer or free end portion of the paper web 5 is positioned to secured it to the support ready to be wound thereon. When the recording operations are completed and the casing 1 is opened, the support 6' is released or detached from the shaft 29 and the support rotated manually to wind thereon the portion carrying time stamp impressions to feed the contiguous unstamped portion into position to be secured to the support 6'. That portion of the web carrying the impressions is then severed from the unstamped portion, and unwound from the support, following which the resulting free end portion of the web is secured to the support 6'.

38 indicates as an entirety the connections between the shaft 20 and the shaft 29, arranged to lock the latter against movement through a predetermined rotative movement of the shaft 20 in each revolution thereof and to rotate the shaft 29 during the remaining rotative movement of the shaft 20. In this operation, the shaft 29 is held against rotation while the platen is operated by the cam 18 and released, so that at the time an impression is made on the paper the latter is at rest, but following the impression on the web, the shaft 29 is rotated to wind the succeeding portion of the web 5 on the support 6' to feed the contiguous portion thereof into position to receive a time stamp impression.

By preference the connections between the shaft 20 and the shaft 29, when operating to rotate the latter and the support 6', wind on the support a portion of the web long enough to move that portion thereof on which the last impression was made by the time stamp devices, into view behind the window 2a, whereby the impression may be checked with the hands of the clock 4. The connections 38 comprise the following: 39 indicates a disk suitably fixed to the shaft 20 below the base 1x and provided on its lower face with a locking element 40 and a series of depending pins 41. The locking element 40 consists of a thickened portion of the disk 39 having an arcuate outer wall 40a struck on a predetermined radius of the shaft 20. The series of pins 41 extend from one side of the locking element 40 around the disk 39 to the opposite side thereof in uniform spaced relation so as to successively move into and recede from uniformly spaced slots 42 respectively, formed in a disk 43, which is secured to the shaft 29 below the base 1x. The slots 42 in the disk 43 extend radially inwardly from its periphery and are uniformly spaced to successively receive the pins 41, the engagement of each pin with the wall of a slot serving to rotate the disk 43. As shown in Fig. 6, one side edge of the disk 43 between two of the adjoining slots 42 is of concave shape from end to end, as shown at 42a, having a curvature concentric to the wall 40a of the locking element 40, and arranged to mesh therewith, as the disks 39 and 43 rotate. Fig. 6 shows the position of the disks 39 and 43 at starting position (see Fig. 2 where pin 27 is in position to enter the adjacent slot 26). If now the shaft 20 is rotated one revolution, which, as already set forth, rotates the disk 23 one step and reciprocates the platen 9 to make an impression on the paper web, the wall 40a will lock the disk 43 against rotation (their complementary relation permitting the locking element 40 to move relative to the wall 42a while coacting with the latter to lock the disk 43 against rotation), until the wall 40a clears the wall 42a, following which the pins 41 will successively engage the walls of the slots 42 to rotate the disk and thus effect rotation of the support 6' to wind a portion of the web 5 thereon. In this connection, it will be noted that in the assembly of the disks 39 and 43 on their respective shafts, they are predeterminedly related so as to revolve the walls 40a and 42a into interlocking relation in each revolution of the shaft 20 in co-ordinated relation with the operation of the cam 18 so as to lock the disk 43 in advance of and during the operation of the platen to effect a time stamp impression, whereby the latter is made while the paper web 5 is at rest.

44 indicates a signaling device for indicating the position of the shaft 20 when it has made one complete revolution to effect an operation of the platen 9 and movement of the disk 23 one step and is ready to start a succeeding operation, the purpose being to prevent over-feed or under-feed of the paper web 5, whereby each time record thereon will be spaced from adjoining records rather than be overlapped and confused. As shown in Fig. 2, the shaft 20 is in starting position; that is, the pin 27 is in position to engage the adjacent slot 26 and the signalling device 44 is visible through the window 2a. If the shaft 20 is rotated to effect an operation, as already set forth, the signalling device, which is operatively connected to a movable part of the

mechanism, will recede from view and re-appear as the pin 27 reaches its starting position, thus indicating to the operator that the shaft 20 has made one complete revolution and is again in starting position.

The signalling device 44 consists of a flag supported on a movable member 45, which is preferably slidably mounted on the bottom wall of the casing section 1a. The slideable member 45 is provided with an elongated slot 45a, which forms a guide way engaged by a plurality of spaced screws 46 supported in the bottom wall of the casing section 1a. A coiled expansion spring 47 suitably anchored at one end and connected at its opposite end to the movable member 45 normally tends to move the latter in one direction against a stop 47a to position the flag 44 at one side of the window 2a. The movable member 45 is provided with a striker 48 normally arranged in the path of movement of a pin 49 depending from the disk 43, and positioned thereon so as to engage the striker 48 to operate the movable member 45 in the opposite direction as the shaft 20 approaches the end of its movement in making one complete revolution. Accordingly, as the shaft 20 completes its movement, the movable member 45 is moved by the pin 49 in opposition to the spring 47 to position the flag 44 behind the window 2a to signal the operator. As already set forth, the shaft 20 is shown in its starting position; accordingly, in the succeeding operation of the shaft 20, the pin 49 will ride the striker 48 following which the movable member 45 will move toward the left (as viewed in Fig. 6) under the influence of the spring 47 against the stop 47a with the striker 48 in position to be engaged by the pin 49, as it revolves with the disk 43, and moved back to the position shown in Fig. 6.

50 indicates a ratchet wheel fixed to the shaft 20 and engaged by a spring operated pawl 51, which is pivotally mounted on the lower side of the plate 1c, to prevent movement of the shaft 20 counter-clockwise (as viewed in Figs. 2, 6 and 8). 52 indicates as an entirety a detection means 48 for indicating on the paper web each movement of the cover section 1b to open or closed position. Of these means, 52a indicates a recess formed in the post 8a. 53 indicates a pin disposed on the opposite side of the paper web 5 and arranged to be projected into the recess 52a, each such operation of the pin serving to punch a hole in the web. The pin 53 is mounted on a lever 54 (see Fig. 7), which is pivotally mounted on a shaft 55, the latter being supported by the side walls of a U-shaped member 56 suitably fixed to the base 1x (see Fig. 3). The lever 54 is normally biased outwardly against a stop 54' by a suitable spring 54a, which is fixed to the bottom wall of the member 56, to position the pin 53 outwardly 60 of the paper web 5. The upper end portion of the lever 54 is provided with cam walls 57, 57a, reversely inclined relative to its outer face, and arranged to be engaged by a lug or projection 58 fixed to the inner face of the adjacent wall of the casing section 1b. As shown in Fig. 7, the lug 58 is disposed below the cam wall 57 so that if the casing section 1b is opened, the lug in riding the cam wall will swing the lever 54 inwardly, the effect of which is to project the pin 53 through the paper web 5 into the recess 52a. Obviously, when the casing section 1b is closed, the engagement of the lug 58 with the cam wall 57a will punch a separate hole in the paper web. Accordingly, a record is made on the paper web 75 each time the casing is opened and closed. The

punched holes serve the purpose of indicating the setting of the mechanism and closing of the casing by a committee in advance of time stamp records being made on the paper web 5 and the opening of the casing by or in the presence of the committee when the records are completed. As the detection means automatically operate each time the casing is opened and each time it is closed, the committee is able to determine whether or not casing has been opened without the proper authority.

Operation.—In a racing contest the casing 1 is submitted to the committee and set in position for operation, as shown in Fig. 1 with space S in registry with the opening 25. The shaft 20 may then be operated by the committee or the owner of the casing to make a time stamp impression, corresponding to space S, and to move holder No. 1 into registry with the opening 25. Thereafter, at the home station, upon arrival of each pigeon, the band is removed from the latter and deposited in that holder which is in registry with the opening 25 and the shaft 20 rotated one revolution following each deposit. If ten pigeons have been entered in the race, the shaft 20 is operated again corresponding to space F which rotates the disk 23 to a point where the holder No. 2 is opposite the pin 27, but as a slot 26 is omitted from the disk in advance of this holder 2, any attempt to again operate the disk and platen will be blocked by engagement of the pin 27 with the side wall of the disk 23. If less than ten pigeons have been entered in the race or less than ten return to the home station, the number of the holder in registry with the opening 25 will indicate how many pigeons did return, so that the committee can determine how many times the mechanism was operated and identify the time stamp impressions on the web 5 therewith.

To those skilled in the art to which my invention relates many changes in construction and widely differing embodiments and applications of the invention will suggest themselves without departing from the spirit and scope of the invention. My disclosures and the description herein are purely illustrative and are not to be in any sense limiting.

What I claim is:

1. In mechanism of the class described, the combination of a casing one wall of which is formed with an opening, and a recording mechanism in said casing and including an operating shaft, a movable member comprising a disk and a plurality of holders extending therefrom and having receiving openings in said disk, the marginal portion of said disk being formed with a slot adjacent each holder, and a disk on said shaft overlapping said first mentioned disk to fit between said holders to lock said member against movement, said last mentioned disk having an operating device arranged to move into and out of one of said slots in each revolution of said shaft to move a succeeding holder into registry with said opening and a recess adjacent said operating device arranged to receive the holder adjacent the slot into which the operating device moves in each operation thereof.

2. In mechanism of the class described, the combination of a casing comprising a main section and a section hinged thereto, of recording mechanism mounted in said casing and including supports for a roll of paper webbing, one of said supports consisting of a drum on which the webbing is wound, spaced posts for

guiding the webbing relative to said mechanism, one of said posts being formed with a recess, a member pivotally mounted in said main section of said casing and disposed outwardly of the webbing and provided with a punching element arranged to be projected through the webbing into said recess, and a device interiorly carried by said hinged casing section arranged to operate said pivoted member each time said hinged casing section is closed or opened.

3. In mechanism of the class described, the combination of a casing one wall of which is formed with an opening, a recording means in said casing, said means including an operating shaft, a member rotatably mounted in said casing and comprising a plurality of designated stations and a stop station adapted to successively register with said opening, the periphery of said member being formed with spaced slots each related to one of said designated stations, said operating shaft being provided with a disk in overlapping relation to the periphery of said member, a pin on said disk arranged to move into and out of one of said slots in each revolution of said operating shaft to rotate said member and successively move the designated stations and stop station into registry with said opening, the engagement of said pin with the periphery of said member when said stop station registers with said opening serving to prevent rotation of said member.

4. In mechanism of the class described, the combination of a casing consisting of a main section and a hinged section therefor, the top wall of said hinged section being formed with a receiving opening and a shaft engaging opening, a recording mechanism within said casing, said mechanism including a driven upright shaft and a driving upright shaft related to said shaft engaging opening, a member removably mounted on the upper end of said driven shaft in spaced relation to the top wall of said hinged section, the periphery of said member being formed with spaced slots, and a pin carried by said driving shaft arranged to move into and out of said slots to rotate said member step by step in each revolution of said driving shaft to effect registry of successive portions of said member with said receiving opening, said pin extending upwardly and arranged to prevent removal of said member from said driven shaft prior to its disengagement from said pin.

5. In mechanism of the class described, the combination of a casing provided with a window in one wall thereof, a recording mechanism in said casing and including a drum on which a web of paper is wound and an operating shaft, driving connections between said shaft and the shaft for said drum arranged to impart one revolution to said drum for each revolution of said operating shaft, said connections including a disk fixed to the drum shaft and provided with a lug, a slide carrying a signal device, an arm on said slide engaging said lug and held thereby to position said signal device in exposed relation to said window, and a spring normally tending to hold said arm in engagement with said lug and to move said slide laterally relative to said window during movement of said disk, whereby said signal device moves out of and into exposed position through said window to indicate the rotative movement of said operating shaft.
